WASTE GRAB PREVENTER

Albert G. Kenyon, Wyoming, R. I.

Application July 14, 1937, Serial No. 153,497

12 Claims. (Cl. 308—89)

This invention relates to the journal and journal box such as are used in railroading; and has for its main object to provide an arrangement which will prevent waste which is in the journal box from being thrown up beneath the brass through which the box is supported on the journal.

Another object of the invention is to utilize any movement of the brass for operating a device to close any gap which may exist between the journal and its bearing so as to prevent any waste from being thrown into said opening to lodge under the brass.

Another object of the invention is to prevent a continual contact of the preventer device with the journal as it rotates, leaving the same normally free for such rotation and to contact the journal and close any passage to the lifting of waste only when abnormal conditions occur in the journal box and journal such for instance as when the car is stopped by bumping or started by excessive jerking pulls or by moving around sharp corners.

With these and other objects in view, the invention consists of certain novel features of construction, as will be more fully described, and particularly pointed out in the appended claims.

In the accompanying drawings:

Fig. 1 is a sectional view through the journal box and journal;

Fig. 2 is a fragmental sectional view similar to Fig. 1 showing the relative movement of the parts of the journal box and journal;

Fig. 3 is a perspective view of the device which is utilized for maintaining the waste in its desired location;

Fig. 4 is a view similar to Fig. 1 showing a modified form of device;

Fig. 5 is a fragmental view of a part of Fig. 4 on a larger scale;

Fig. 6 is a face view of the device shown in Fig. 4 detached from the journal and box;

Fig. 7 is a sectional view of the device alone on substantially line 7—7 of Fig. 6;

Fig. 8 is a sectional view on line 8—8 of Fig. 6, with the parts in a different position than shown in Fig. 7;

Fig. 9 is a sectional view on line 9—9 of Fig. 6;

Fig. 10 is a perspective view of a fragmental portion of the arm which contacts the journal upon movement of the brass of the box.

In railroading, as the weight of cars and the power to move them increase, it often occurs that waste is thrown up beneath the brass of the journal box which causes excessive friction and

heating of the bearing. The lodging of the waste up under the brass of the bearing is believed to be caused at the time when some shock occurs, such for instance as by the freight car in the freight yard being allowed to roll from the hump 5 toward other cars which are stationary and allowed to bump the other cars in order that it come to rest. The speed which such a rolling freight car attains is often eight to ten miles an hour when such bump and shock occurs, and 10 when such shock occurs the body of the car can be seen to raise, thus relieving any pressure upon the brass through which the weight of the car is supported and allowing this brass to shift its position on the journal or even lift with reference thereto. Also, when a heavy train starts by successively taking up the slack which occurs between the draw bars of different cars each time the successive pull and shock occurs the cars will lift, and this same action occurs when the cars 15 are drawn around sharp curves so that at each one of these liftings the weight on the car is relieved, allowing the brass to lift, and if some waste should fly from its normal position at this time, as it might well do by reason of such shock, the 20 same might lodge beneath the brass, which is objectionable, and will cause heating. It is also objectionable to have any device constantly contacting the journal and frictioning therewith as it disturbs the oil film for lubricating the journal 25 in its bearing; and in order to permit this oil to maintain its lubricating film undisturbed by contacts with any parts of the journal, I have provided a device for preventing the flying of waste beneath the brass by reason of its movement; and I cause the movement of the brass to actuate the 30 device and move it into contact with the journal so that there will be no opening permitted between the journal and the brass to permit the waste from flying up and lodging beneath the brass, thus, the device ordinarily allows free running of the journal in its bearing and also blocks the entrance of any waste beneath the brass; and the following is a more detailed description of the present embodiment of this invention, illustrating the preferred means by which these 35 advantageous results may be accomplished:

With reference to the drawings, 10 designates the journal upon which the wheels of a car, such as a freight car, are fixed so as to turn with the 40 wheels as they roll along the tracks, and 11 designates generally the journal box which is attached to the truck of the car and through which weight is applied to the journal. This journal box consists of a casing 12 having a saddle 45

piece 13 and brass 14 of an upper frustro pyramidal shape fitting in a similarly shaped recess 15 in the saddle with babbittting material 17 located in the brass 14 which contact with the journal 10. The lower part of the casing contains waste 18 which is maintained saturated with some lubricant which causes a film of the lubricant to be disposed over the surface of the journal and lubricate the journal in its contact with the babbittting material in the brass.

When the casing is subjected to severe shocks or sharp turns or some such action it often occurs that the car tends to raise from the journal 10 under such conditions, there being shown in Fig. 15 a relation of the parts when such conditions occur; and in this case when the saddle 13 and casing 12 lift there is an opportunity for the brass 14 which is then loose within the saddle 15 to shift its position and at the same time lifting, 20 as illustrated in Fig. 2, and at such times under such shocks the waste will jump up and under some conditions will enter the space 20 between the journal and the brass 14 which will cause heating of the bearing and detrimental action 25 thereto; and in order to prevent this jumping upwardly of the waste I have provided a plate 21 which is secured through openings 22 by means of bolts 23 to the sides of the casing 12. The upper portion of the plate 21 is inclined inwardly 30 as at 24 to provide an arm which is bent over as at 25 to provide a journal engaging edge 26 which is scalloped or provided with projecting portions 27 and recesses 28. The material is of a resilient or elastically bendable character with the convex rolled curved portion 25 in a location to contact with the edges 48 of the brass 14 so that should the brass shift its position relative to the journal 10, such as shown in Fig. 2, the edge 48 of the brass will force the inwardly inclined portion 24, 25 and 26 of the guard inwardly so that the edges 27, 28 will contact with the journal, such as shown at the left in Fig. 2 and thus prevent any waste as at 29 from jumping up between the journal and the brass to become lodged 45 therein as soon as the weight of the car causes the brass to move back into its normal position, such as shown in Fig. 1.

In some instances instead of utilizing the simple form of guard shown in Figs. 1, 2 and 3 50 I may provide a double acting guard such as shown in Figs. 4 to 10 inclusive. In this instance a bracket 33 is provided with openings 31 through which bolts 32 extend to secure the same to the casing 12. This bracket supports a pivot 55 pin 33 upon which a unit 35 is pivotally mounted, this unit having a downwardly extending arm 36 and an upwardly extending arm 35' with a hook-shaped portion 37 suitably secured to the upper portion of the arm by means of a bolt 38. These 60 arms are separate but both are mounted adjacent to each other on pivot pin 33. The lower arm 36 is provided with a projection or stop member 36' which extends above the pivot pin 33 and in position to engage a portion of the upper arm 35' and 65 a coil spring 33' extends about this pivot and has portions engaging the arms to urge them to swing towards each other against the stop 36' so they will move about the pivot as a unit, although under certain conditions one will move with reference to the other. The edge of the lower portion of the arm 36 is scallop-shaped or provided with projections 39 and recesses 40 and the engaging edge of the hook 37 is similarly shaped with projections 41 and recesses 42 both for suitable engagement with the journal 10 upon cer-

tain relative movements of the journal and bearing. A coil spring 43 extends about the pivot pin 33 with one end portion 44 engaging the upper portion of the arm 35' while the other end portion 45 engages the bracket 30 so as to tend to swing the unit 35 about its pivot with its upper end knuckle 46 engaging the lower edge 47 of the brass. This arrangement is provided on opposite sides of the journal and box with the parts relatively formed in opposite directions.

Should a shifting of the brass occur, as shown in Fig. 2, the portion 47 of the brass in Fig. 4 will act against the knuckle 46 of the guard to swing the same as a unit about its pivot so as to cause the lower portion 36 of the arm to contact the journal and provide a pocket between the lower portion of the arm and the bracket 30 to prevent the jumping of waste upwardly to lodge in the opening 20 between the brass and the journal. The upper arm 35' being movable 20 away from engagement with the stop 46' should movement of the brass continue after the arm 36 contacted the journal, while at the same time the spring acting about the pivot on the opposite guard would cause its edge 41, 42 to engage 25 the journal and effectively prevent any movement of the waste upwardly into a location between the brass and the journal on this side of the journal, whereby an effective means is provided on both sides of the journal box for preventing the jumping of the waste upwardly into 30 a location where the bearing occurs.

By these arrangements the waste is prevented from jumping up under the brass while at times of normal running there is no contact of the 35 device with the journal.

The foregoing description is directed solely towards the construction illustrated, but I desire it to be understood that I reserve the privilege of resorting to all the mechanical changes to which 40 the device is susceptible, the invention being defined and limited only by the terms of the appended claims.

I claim:

1. In combination with a journal, a journal 45 box having a brass through which the weight applied to the journal box is supported on the journal, an arm in close proximity but spaced from the journal supported by said journal box, said arm being in contact with said brass, said 50 parts being so arranged that a movement in one direction by said brass will move said arm into contact with the journal to prevent the passage of waste from a position below said arm to a position above said arm and beneath said brass.

2. In combination with a journal, a journal box having a brass through which the weight applied to the journal box is supported on the journal, a resilient arm supported by said journal box in close proximity but spaced from the 60 journal, said arm being in contact with said brass, said parts being so arranged that a movement in one direction by said brass will move said arm through its resiliency into contact with the journal to prevent the passage of waste from 65 a position below said arm to a position above said arm and beneath said brass.

3. In combination with a journal, a journal box having a brass through which the weight applied to the journal box is supported on the 70 journal, an arm supported by said journal box and having a hook-shaped portion in close proximity but spaced from the journal, said arm being in contact with said brass, said parts being so arranged that a movement in one direction by 75

said brass will move the hook-shaped portion of said arm into contact with the journal to prevent the passage of waste from a position below said arm to a position above said arm and beneath said brass.

4. In combination with a journal, a journal box having a brass through which the weight applied to the journal box is supported on the journal, an arm supported by said journal box and having a hook-shaped terminal portion in close proximity but spaced from the journal, said arm being in contact with said brass, said parts being so arranged that a movement in one direction by said brass will engage and move the hook-shaped terminal portion of said arm into contact with the journal to prevent the passage of waste from a position below said arm to a position above said arm and beneath said brass.

5. In combination with a journal, a journal box having a brass through which the weight applied to the journal box is supported on the journal, a resilient arm supported by said journal box and having a hook-shaped terminal portion in close proximity but spaced from the journal, said arm being in contact with said brass, said parts being so arranged that a movement in one direction by said brass will engage and move the hook-shaped terminal portion of said arm through its resiliency into contact with the journal to prevent the passage of waste from a position below said arm to a position above said arm and beneath said brass.

6. In combination with a journal, a journal box having a brass through which the weight applied to the journal box is supported on the journal, an arm pivotally supported by said journal box and located in close proximity to but spaced from the journal, said arm having a portion in contact with said brass, said parts being so arranged that a movement in one direction by said brass will move said arm into contact with the journal to prevent the passage of waste from a position below said arm to a position above said arm and beneath said brass.

45 7. In combination, a journal and journal box, a brass in the box through which the weight which is applied to the journal box is supported on the journal, and resilient guard means positioned between one side of the journal and the adjacent wall of the journal box so constructed and arranged as to be out of contact with the journal when the brass is in normal position and responsive to movement of the brass for moving into contact with the journal to prevent any waste or other particles located beneath the journal from jumping up into a position beneath the brass.

8. In combination with a journal, a journal box having a brass through which the weight applied to the box is supported on the journal, waste in the journal box, and a pair of resilient guard members positioned one at either side of the journal between it and the journal box engageable with one of the parts mentioned, each of said guard members being so constructed and arranged as to be normally out of contact with

the journal when the brass is in normal position and responsive to abnormal conditions occurring with relation to the parts caused by a relative movement of the said associated parts for moving into contact with the journal to prevent the movement of the waste in the journal box from entering beneath the brass.

9. In combination with a journal, a journal box having a brass through which the weight applied to the journal box is supported on the journal, an arm pivotally located on each side of the journal box, said arms on opposite sides facing in opposite directions, and means arranged for urging said arms toward said journal, each of said arms having a portion extending beneath its pivot and a portion above its pivot, said arms being so constructed and arranged as to be oppositely rockable upon movement of the brass so that the part above the pivot of one and the part below the pivot of another contact said journal upon movement of the brass.

10. In combination with a journal, a journal box having a brass through which the weight applied to the journal box is supported on the journal, an arm located on each side of the journal box, each arm being pivotally supported by said journal box and located in close proximity but spaced from the journal, each arm having a portion in contact with said brass, said parts being so constructed and arranged that a movement in one direction by said brass will move said arm into contact with the journal to prevent the passage of waste from a position below said arm to a position above said arm and beneath said brass.

11. In combination with a journal, a journal box having a brass through which the weight applied to the journal box is supported on the journal, an arm pivotally located on each side of the journal box, said arms on opposite sides facing in opposite directions, each of said arms having a portion extending above and a portion extending beneath its pivot, said arms being so constructed and arranged as to be oppositely rockable upon movement of the brass so that the part above the pivot of one and the part below the pivot of another contact said journal upon movement of the brass, and resilient means moving each arm about its pivot into contact with the brass.

12. In combination with a journal, a journal box having a brass through which the weight applied to the journal box is supported on the journal, an arm located on each side of the journal box, each arm being pivotally supported by said journal box and located in close proximity but spaced from the journal, each of said arms having a portion above its pivot in contact with said brass, said parts being so constructed and arranged that a movement in one direction by said brass will move one of said arms into contact with the journal to prevent the passage of waste from a position below said arm to a position above said arm and beneath said brass.

ALBERT G. KENYON.
